(57) CLAIM

The ornamental design for the furniture base, as shown and described.

DESCRIPTION

FIG. 1 is a perspective view of an furniture base in accordance with the present invention;

FIG. 2 is a front view of the furniture base, the back of the furniture base is not illustrated as it forms no part of the present invention; and,

FIG. 3 is a right side view of the furniture base, the left side view being a mirror image thereof.

The broken line showing of a furniture top is for illustrative purposes only and forms no part of the claimed design.
